UNITED STATES PATENT OFFICE.

PETER L. ROBERTSON, OF MILTON, NEAR HAMILTON, ONTARIO, CANADA.

BLANK-FEEDING DEVICE.

1,052,092.

Specification of Letters Patent. Patented Feb. 4, 1913.

Original application filed December 27, 1910, Serial No. 599,548. Divided and this application filed June 2, 1911. Serial No. 630,890.

To all whom it may concern:

Be it known that I, PETER LYMBURNER ROBERTSON, of Milton, near Hamilton, in the Province of Ontario, Canada, have invented certain new and useful Improvements in Blank-Feeding Devices; and I do hereby declare that the following is a full, clear, and exact description of the same.

The invention forming the subject-matter 10 of this application, which is a divisional part of application Serial No. 599,548, filed Dec. 27, 1910, is especially adapted for use in feeding screw blanks to screw forming mechanism, and it has for an object to provide a blank feeding means which will be simple in construction and which will also be more positive in action than those heretofore known.

Other objects and the advantages of the 20 invention will be apparent to those skilled in the art from a consideration of the following description and accompanying drawings forming a part of this specification in which one embodiment of the invention has been 25 described and illustrated and in which similar reference characters indicate the same parts throughout the various views and wherein—

Figure 1 is a front elevation of my improved blank feeding means showing it applied to a screw machine, portions of the latter being shown; Fig. 2 is a perspective view of one of the main members of the device; Fig. 3 is a vertical sectional view taken 35 on line 3—3 Fig. 1, the parts being in the position shown in Fig. 5; Fig. 4 is a detail face view of parts of the operating mechanism for the oscillatory feed arm; Fig. 5 is a plan view of the device; Fig. 6 is a 40 vertical sectional view taken on line 6—6 Fig. 5; Fig. 7 is a detail view showing the mounting of the oscillatory feed arm; Fig. 8 is a detail inverted plan view of a portion of the oscillatory feed arm operating means; 45 Fig. 9 is a detail side elevation of the hopper and the hoist operating means; Fig. 10 is a vertical sectional view taken on line 10—10 Fig. 7; Fig. 11 is a detail sectional view of a portion of the hoist operating 50 means; Fig. 12 is a detail perspective view illustrating particularly the relation of the oscillatory arm to the notched disk when in position receiving a blank from the latter.

In the drawings the bed plate of the 55 screw machine to which my invention is

shown applied is indicated at 1 and may be supported on suitable legs, not shown. The pointing tool indicated at 3, the threading tool 4, back rest 5, the pick out device 8 for taking the finished screw from the 60 chuck, 6, and the trip device 9 for releasing the screw from the pick out device, which parts comprise portions of the screw machine, form no part of the present invention having been fully disclosed and 65 claimed in the application above referred to, while the chuck 6, the jaws whereof are indicated at 7, has been made the subject-matter of a separate divisional application filed by me June 2, 1911 under Serial No. 70 630,889.

My improved blank feeding device comprises two main parts or members one of which is adapted to receive the blanks, indicated at α , from a suitable device as the 75 inclined chute 14 formed by a pair of vertically arranged parallel strips on the tops of which the heads of the blanks rest with their shanks or bodies hanging down therebetween, the blanks being delivered to the 80 upper end of the chute by suitable means, to which further reference will be presently made, from a suitable hopper 15, mounted upon a standard 16 on the bed plate 1. The other main part or member is adapted to receive the blanks from the first member and deliver them to the chuck 6. The first of 85 these parts consists, briefly speaking, of a rotatably mounted member adapted to receive the blank and operated by suitable 90 means to cause it to advance the blank to the desired point. In the present embodiment of my invention this part of the feeding mechanism is formed as follows: A horizontal disk 29 is located adjacent to the 95 lower end of the chute and has its periphery formed with notches or recesses 30 to receive the blanks which are delivered thereto in vertical position. This disk is rigidly secured on the upper end of a vertical spindle 100 31 rotatable in a bearing bracket 31' on the upper face of which the disk rests freely, the bracket being secured upon a part of the standard 16. The disk 29 is intermittently rotated by means of a ratchet wheel 105 32 rigid on the lower end of the spindle 31 and which is operated by a pawl 33 pivoted to a link 34 having legs 35 which inclose the ratchet wheel and are pivoted thereto at one end. The opposite end of the link 34 is con- 110

nnected to a second link 36 which receives motion from a lever 37 to one end of which it is connected, such lever being fulcrumed between its ends as at 38 to a suitable part 5 of the standard 16 and being operated by a cam 39 engaging a roller 40 on the opposite end thereof, the cam 39 being mounted on a shaft 30^a supported and operated in any suitable manner, not shown. The blanks 10 are retained in the notches 30, while they are being advanced by the rotation of the disk, by means of a substantially semi-circular retaining member in the form of a resilient strap 41 which partially surrounds 15 the notched periphery of the disk 29 and which acts in conjunction with a second member or strap 42 inwardly of and parallel to the strap 41, these straps being secured at one end to and forming a continuation 20 of the chute 14.

The second part or member of the feeding mechanism consists briefly speaking of an oscillatory arm adapted to take the blank from the first member and operated by suitable means to cause it to deliver the blank to the chuck 6. In this embodiment of my invention this second part of the feeding mechanism comprises an oscillatory arm 50 which oscillates from a substantially horizontal position, shown in Figs. 3 and 4, in which it receives the blank from the disk 29, to a substantially vertical position, shown in Figs. 1 and 7, in which latter position the blank is in position to be engaged 35 by the jaws of the chuck. The arm 50 is provided on its outer or free end with a spring bill 51 which, when the arm is in the position shown in Fig. 5, is underneath the recessed portion of the disk 29 and into 40 which the rotation of the disk forces the blank, the arm being oscillated by a short horizontal rocker shaft 53 freely supported in a sleeve 54 formed integrally with the standard 16, the shaft having rigidly secured to one end thereof a block 55 in which the inner end of the arm 50 is revolvably mounted. This shaft is operated by a crank pin 57 projecting from a disk 58 on the end 45 of the shaft and carrying a roller 58' engaging a slot 59 in a disk 60. This disk has a vertical boring in which is rigidly secured a rod 61 the ends whereof project through the walls of a cylindrical housing 62 which incloses the disks 58 and 60 and is secured 55 by a set screw 63 on the reduced end 64 of the sleeve 54. The rod 61 is reciprocated to oscillate the disk 58 (through the medium of disk 60 and pin 57) respectively by a single throw cam 64 on shaft 39^a and a retractile helical spring 61' secured at one end 60 to the top of the rod and at its other end to the lower part of the housing 62, the spring moving the arm 50 toward the chuck and the cam returning it.

65 In order to cause the blank to be deliv-

ered to the gripping device with its head in advance of the arm 50 so as to be readily engaged by the gripper the arm is also rotated on its own axis substantially a half turn in opposite directions as it swings 70 from one position to the other. This I accomplish by means of a small bevel gear or pinion 66 rigid on arm 50 and engaging a larger segmental bevel gear 67 secured by a set screw 68 on the reduced end 69 (opposite to end 64) of the sleeve 54.

As will be seen by referring particularly to Figs. 1 and 8 the pinion 66 disengages from the segmental gear 67 before the arm 50 has reached the limit of its downward swing while the gear and pinion are relatively so arranged as to cause the arm to have made the required half turn when the gears disengage. The purpose of this construction is to obviate any chance of the 35 head of the blank striking one of the jaws 7 of the chuck 6, a cut away portion 66' on the pinion sliding on a cut away portion of the gear 67, the arm being limited in its movement by a rib 67' on the gear.

90 The means which I prefer to employ to deliver the blanks from the hopper to the chute comprises a slotted hoist 75, and in order to obviate any chance of damage to the machine through the hoist sticking (as 95 might be caused by the blanks in the hopper obstructing the movements thereof) I have devised a mechanism for operating the hoist which provides a yielding or displaceable connection between the hoist and 100 the initial driving gear. As here shown the hoist is vertically reciprocated by means of a connecting rod 76 pivoted thereto at its upper end and receiving motion from a crank disk 77 to which its lower end is connected. This disk 77 is rigidly mounted on a stub shaft 78 supported in bearings 79 on the base 16' of the standard 16. A second disk 80 is also rigidly mounted on the stub shaft 78 and is operatively engaged 105 and rotated by a sprocket wheel 81 by means of a bolt 82 slidable in a boring 82' in disk 80 the beveled end 83 of which projects slightly into a boring 84 in the sprocket wheel 81, a spring 85 normally holding the 110 bolt in such position, a collar 86 on the bolt limiting the inward movement. It will readily be seen that in the event of the hoist sticking the spring will yield and allow the beveled end of the bolt to disengage from 115 the boring. The sprocket wheel 81 is driven by means of a sprocket chain 87 looped thereover and over a second sprocket wheel 88 on the shaft 39^a, and is freely mounted 120 on shaft 78.

125 In the operation of my improved feeding device, the blanks are first placed in the hopper and are lifted to the chute by the hoist 75 (the blanks being caught in the slotted upper end of the chute in a well 130

known manner). The blanks travel down the chute 14 by gravity and as each blank reaches the bottom of the chute it enters one of the notches 30 in the disk 29 and is carried around as the disk is rotated (through 5 ratheet wheel 32, pawl 33 etc.) until it is forced into the spring bill 51 on the arm 50, the straps 41 and 42 retaining the blank 10 in proper position in the notches 30 during the rotation of the disk. The arm 50 is then operated (through shaft 53, gears 66, and 67, etc.) to swing it to a vertical position with the blank having its head facing toward the chuck and being in position to 15 be engaged by the jaws of the latter, the arm 50 swinging back to horizontal position after the chuck has seized the blank.

I claim:

1. The combination with mechanism for 20 acting upon a blank, of blank feeding means including a rotary member adapted to receive and advance a blank, means retaining such blank while being advanced by the rotary member with its end projecting from 25 such rotary member parallel to the axis thereof, an oscillatory arm provided with a blank gripping device adapted to oscillate from a position with its blank gripping device adjacent to the said rotary member and 30 in the path of movement of the said projecting portion of the blank held thereby to a position adjacent the said mechanism for acting upon the blank, and means for operating the said rotary member to cause it to 35 move the blank into engagement with the gripping device of the oscillatory arm when the latter is adjacent the said rotary member.
2. In a blank feeding device, in combination, an oscillatory feed arm provided with 40 a clip, a rocker shaft to one end of which said arm is connected, a reciprocatory rod located near the other end of the shaft, means for reciprocating the rod, and means 45 operatively connecting the rod and shaft to cause reciprocation of the rod to rock the shaft, including a disk rigid upon the rod and formed with a slot, and an eccentric pin carried by the shaft and engaging in 50 the said slot.
3. In a blank feeding device, in combination, a frame, an arm provided with means for holding a blank, means pivoting the arm to the frame, means for causing the arm to

swing upon its pivot point, and means acting synchronously with such last mentioned means to cause such arm to have revoluble motion imparted thereto, for the purpose set forth.

4. In a blank feeding device, in combination, a frame, an arm provided with means for holding a blank, means pivoting the arm to the frame, means for causing the arm to swing upon its pivot point, and means for causing the said arm to revolve upon its own axis.

5. In a blank feeding device, in combination, an oscillatory arm provided with means for holding a blank, means for oscillating the said arm, and means for causing the said arm to revolve upon its own axis, including a pair of intermeshing gears mounted one upon the arm and the other upon the machine frame.

6. In a blank feeding device, in combination, a rocker shaft, an oscillatory arm provided with means for holding a screw blank, and swiveled upon the rocker shaft, a bevel pinion mounted on the arm, a stationary bevel gear intermeshing with the said pinion, and means for rocking the said shaft, for the purpose set forth.

7. In a blank feeding device, in combination, a rocker shaft, an oscillatory arm provided with means for holding a blank, 85 and swiveled upon the rocker shaft, a bevel pinion mounted on the said arm, a stationary segmental bevel gear intermeshing with the said pinion, and means for rocking the said shaft, for the purpose set forth.

8. In a blank feeding device, in combination, a rotatable disk formed with recesses adapted to receive a blank, retaining means acting in conjunction with the said recesses, operating mechanism applied to the said disk, an oscillatory arm adapted to receive the blank from the disk, means for oscillating the said arm, and means for causing the said arm to revolve upon its own axis.

In testimony whereof, I have signed my name to this specification, in the presence of two subscribing witnesses.

PETER L. ROBERTSON.
